F. H. LAMB.
LOGGING BLOCK.
APPLICATION FILED NOV. 26, 1919.

1,367,058.

Patented Feb. 1, 1921.

UNITED STATES PATENT OFFICE.

FRANK HAINES LAMB, OF HOQUIAM, WASHINGTON.

LOGGING-BLOCK.

1,367,058.

Specification of Letters Patent.

Patented Feb. 1, 1921.

Application filed November 26, 1919. Serial No. 340,739.

To all whom it may concern:

Be it known that I, FRANK H. LAMB, a citizen of the United States, residing at Hoquiam, in the county of Grays Harbor 5 and State of Washington, have invented certain new and useful Improvements in Logging-Blocks, of which the following is a specification, reference being had therein to the accompanying drawing.

10 This invention relates to certain new and useful improvements in logging blocks, the object being to provide a block which is exceedingly simple and cheap in construction and one which can be readily assembled, the 15 pulley spindle being secured within the frame by nuts operated by the rotation of the side members of the frame, so as to securely fasten the spindle in position.

Another and further object of the invention 20 is to provide novel means for locking the latch pins in position.

A still further object of the invention is to provide a logging block having novel means for lubricating the pulley in connection 25 with the spindle whereby the pulley will be thoroughly lubricated.

A further object of the invention is to provide a novel form of self-closing plug, for the oil reservoirs of the block, whereby 30 the reservoirs can be readily filled with lubricant.

Other and further objects and advantages of the invention will be hereinafter set forth and the novel features thereof defined by the 35 appended claims.

In the drawings:

Figure 1 is a side elevation of a logging block constructed in accordance with my invention partly in section, showing the manner 40 of locking the latch pin in position.

Fig. 2 is an end elevation partly in section showing the manner of constructing the oil reservoir and spindle.

Fig. 3 is a detail enlarged section through 45 the self-closing oil plug for the oil reservoir.

In carrying out my invention I employ a frame formed of side members 1 and 2, which are provided with spaced apertured ears 3 and 4, at their upper ends through 50 which extend latch pins 5 and 6. The latch pins are provided with annular grooves 7 from which extend longitudinal grooves 7' as clearly shown in Fig. 1. The ears of the side members of the frame are provided 55 with set screws 8 extending into the aper-

tures thereof for locking the latch pins in position. By forcing the latch pins into the apertured ears so that the set screws will pass through the longitudinal groove into the annular groove and by turning the latch 60 pin it will be securely locked within the frame.

The side members 1 and 2 are connected together through the medium of a link 9, which is provided with apertured ends 65 through which the latch pins 5 and 6 extend. Mounted on the latch pins 5 and 6 between the ears of the side members is a yoke 10, which is provided with bifurcated apertured ends 11, which embrace the link 9, the latch 70 pins passing through the apertured ends of the furcations as clearly shown in Fig. 1.

The side members 1 and 2 are provided with bores 12 and 13 adapted to receive the reduced ends 14 and 15 of a spindle 16, on 75 which is mounted a pulley 17, which is so disposed between the side frames that it can rotate freely thereon, the side frames being provided with guide portions 18 for guiding and holding the cable or pulley. 80

The spindle 16 is provided with a longitudinally disposed bore 19, which is closed at its outer end by a plug 20, and is provided with radial bores 21 forming oil passages which are adapted to communicate with 85 oil reservoirs 22 formed in the side members 1 and 2, said oil reservoirs extending down around the bores 12 and 13, thereof as clearly shown in Fig. 2. Extending radially from the bore 19 of the spindle are ducts 23, 90 which terminate in a groove 24, formed in the periphery of the spindle into which is adapted to be placed a strip of felt for lubricating the bushing of the pulley as it will be seen that oil from the reservoirs 22 will 95 pass through the oil passages 21 into the bore 19, and out through the ducts 23 into the groove 24, so as to saturate the strip of felt therein.

The oil reservoirs are provided with 100 threaded bores 26 in which are mounted hollow plugs 27, each having a conical valve seat 28, on which is adapted to be seated the conical portion of valve 29, which is held closed by a coil spring 30, as clearly shown 105 in Fig. 3, whereby an oil can or any other device can be forced into engagement with the valve so as to unseat the same in order to allow lubricant to be placed within the oil reservoirs 22. 110

The reduced ends of the spindle 15 are threaded as shown at 31 on which is adapted to be placed nuts 32, adapted to fit within recesses 33 formed in the side members 1 5 and 2, and as herein shown the recesses and nuts are hexagon in shape, but it is of course understood that I do not wish to limit myself to a peculiar shape of nut or a peculiar shape of recess as any shape of nut or recess 10 can be employed provided that the shape of the recesses correspond with the shape of the nuts. The recesses 33 form sockets and in connection with the members 1 and 2 form wrenches by means of which the nuts can 15 be rotated as will be hereinafter fully described.

In assembling a logging block constructed in accordance with my invention, the two side members 1 and 2 are placed over the 20 reduced ends of the spindle, it of course being understood that the pulley has previously been placed upon the spindle. A wrench is then preferably applied to the nuts so as to screw the same until they start to 25 enter the recesses and by moving the side members so that the nuts will enter the recesses or sockets and then rotating the members 1 and 2 the nuts will be screwed up on the threaded ends of the spindle so as to 30 securely lock the spindle without the use of any other kind of fastening means.

The yoke and links are then placed in position and the latch pins forced through the same, it of course being understood that 35 in inserting the latch pin the same is turned until the longitudinal groove registers with the projection formed by the set screw 8 so that the pin will pass into the ear and by turning the latch pin so as to move the projection out of alignment with the longitudinal groove the pin is securely locked. The reservoirs can then be filled with oil and in use the logging block will be thoroughly 40 lubricated.

45 From the foregoing description it will be seen that I have provided a logging block composed of a pair of independent side members having bores to receive a spindle, said members being provided with sockets 33 adapted to receive nuts carried by the ends 50 of the spindle whereby upon rotation of the side members the spindle will be securely locked between the side members of the frame of the logging block.

55 By constructing a logging block of a pair of duplicate side members each having a nut receiving socket for rotating the nut on the spindle, the spindle can be securely locked within the side members. It will also 60 be seen that by constructing the latch pins with annular grooves from which extend longitudinal grooves and by forming the ears of the side members with projections herein shown in the form of a set screw the 65 pins can be readily inserted and by giving

the same a turn will be locked in position. While I have shown the side members connected together at the upper end by latch pins and links it is of course understood the solid cross head could be bolted between the 70 upper ends of the side members having a swivel or clevis connected thereto and I do not wish to limit myself to these details of construction.

What I claim is:

75 1. A logging block composed of a pair of members connected together at their upper ends by a link and yoke, said members being provided with bores to receive a spindle, said spindle having threaded ends, nuts so mounted on said ends, said members being provided with sockets adapted to receive said nuts for rotating said nuts for securing said spindle in said side members.

85 2. A logging block comprising a pair of side members having bores to receive the spindle, each of said members being provided with a socket adapted to receive a nut carried by said spindle for rotating said nut for locking said spindle between said side 90 members.

95 3. A logging block comprising a pair of side members provided with bores, a spindle mounted in said bores having threaded ends, a nut mounted on each threaded end, said members being provided with sockets corresponding in shape to the nuts for rotating said nuts, when turned around the spindle as an axis, for locking said spindle between said side members.

100 4. A logging block comprising a pair of side members having bores at their lower ends, a spindle having reduced threaded ends mounted in said bores, a pulley mounted upon said spindle, nuts mounted on said threaded ends, the side members of said frame being provided with sockets to receive said nuts for rotating said nuts when said side members are turned around the spindle as an axis for locking said spindle between 110 said side members and a yoke for connecting the upper ends of said side members.

115 5. A logging block composed of a pair of side members, a spindle carrying a pulley mounted in said side members, said spindle being provided with threaded portions, nuts working on said threaded portions, said members being provided with sockets corresponding in shape to said nuts, said members being adapted to be rotated around the 120 spindle as an axis, for revolving said nuts for securing said spindle between said side members, and means for connecting the upper ends of said side members.

125 6. A logging block comprising a frame formed of a pair of side members, connected together at their upper ends by a yoke, said members being provided with bores, a grooved spindle provided with reduced ends mounted in said bores, a pulley carried by 130

said spindle, said spindle having a bore provided with closed ends and with radial passages, one of said side members being provided with an oil reservoir surrounding said bore and communicating with one set of passages, the other set of passages, of said spindle terminating into the groove formed in the periphery thereof, a strip of felt arranged in said groove for lubricating the 10 pulley mounted on said spindle.

7. A logging block comprising a frame composed of side members having bores, a grooved spindle mounted in said bores, a pulley carried by said spindle, a yoke for 15 connecting the upper ends of said side members, said spindle being provided with a bore having closed ends, radial oil passages and oil ducts extending from said bore, said oil ducts terminating in the groove formed 20 in the periphery of said spindle, a strip of felt arranged within said groove, one of said side members being provided with an oil reservoir surrounding said bore and communicating with the oil passages of said

spindle, said oil reservoir having a bore, 25 and a plug arranged within said bore.

8. A logging block comprising a frame composed of side members having bores, a hollow spindle mounted in said bores having closed ends, said spindle having a longitudinal groove, a pulley mounted on said spindle, radial oil passages and oil ducts extending from the cavity of said spindle, said oil ducts terminating in the groove formed in the periphery of said spindle, a 35 strip of felt arranged within said groove, said side members being provided with oil reservoirs surrounding said spindle and communicating with the oil passages thereof and means for locking said spindle within 40 said side members.

In testimony whereof I hereunto affix my signature in the presence of two witnesses.

FRANK HAINES LAMB.
